(57) **CLAIM**

The ornamental design for an electric shaver, as shown and described.

DESCRIPTION

FIG. 1 is a perspective view of an electric shaver showing my new design.

FIG. 2 is a front view thereof.

FIG. 3 is a rear view thereof.

FIG. 4 is a left side view thereof.

FIG. 5 is a right side view thereof.

FIG. 6 is an enlarged top view thereof.

FIG. 7 is an enlarged bottom view thereof; and,

FIG. 8 is a rear, right, bottom perspective view thereof. The broken lines in the drawings depict portions of the electric shaver that form no part of the claimed design.
